UNITED STATES PATENT OFFICE.

ROBERT B. CAMPBELL, OF JOLIET, ILLINOIS, ASSIGNOR OF ONE-HALF TO HIMSELF AND ONE-HALF TO WILLIAM Q. OLDEN, OF CHICAGO, ILLINOIS.

STEEL SIDE-DUMP CAR.

No. 866,620.

Specification of Letters Patent.

Patented Sept. 24, 1907.

Application filed September 29, 1906. Serial No. 336,744.

To all whom it may concern:

Be it known that I, ROBERT B. CAMPBELL, a citizen of the United States, residing at Joliet, in the county of Will, State of Illinois, have invented certain new and 5 useful improvements in Steel Side-Dump Cars, of which the following is a specification, reference being had to the accompanying drawings.

My invention relates to steel side dump cars, and one of the principal objects sought to be attained is the construction of a new and improved form of car from which 10 the load may be dumped at either side of the track, or at both sides simultaneously.

Another object of my invention is to provide new and improved mechanism for operating the swinging doors 15 that close the openings through which the load is discharged.

It is also one of the objects of the invention to provide a construction that will insure great strength to the car, and one wherein the strains incident to the use of such 20 a car will be distributed throughout the structure.

I attain these objects as illustrated in the drawings, and as hereinafter fully described.

In the drawings:—Figure 1 is a side elevation of my improved car. Fig. 2 is a diagrammatic longitudinal section. Fig. 3 is a side elevation of one end of the car, some parts being in section, and others broken away to more fully illustrate the means employed for operating the doors at one side of the car. Fig. 4 is a cross section taken at line 4 4 of Fig. 1. Fig. 5 is a view similar to 30 Fig. 4, but showing the doors at each side in their raised or closed position. Fig. 6 is a view similar to Figs. 4 and 5, but showing both doors in their lower or open position. Fig. 7 is a cross section at line 7 7 of Fig. 1. Fig. 8 is a plan view of the supporting frame, taken at line 8 8 of Fig. 7. Fig. 9 is a vertical section illustrating the mechanism for operating the doors, such section being taken at line 9 9 of Fig. 16. Fig. 10 is a cross section taken at line 10 10 of Fig. 9. Fig. 11 is a detail illustrating the manner of hinging the doors, the view 35 being a section at line 11 11 of Fig. 4. Fig. 12 is a side elevation of the devices shown in Fig. 9. Fig. 13 is a detail illustrating the parts shown in Fig. 9 and being section taken at line 13 13 of Fig. 16. Fig. 14 is a cross section taken at line 14 14 of Fig. 9. Fig. 15 is a cross section taken at line 15 15 of Fig. 9. Fig. 16 is a cross section taken at line 16 16 of Fig. 9. Fig. 17 is a plan view of the supporting frame, as in Fig. 8, but differing from Fig. 8 in showing the strengthening plate that is secured to such frame in place thereon. Fig. 50 18 is a plan view of the car-body.

Referring to the several figures of the drawings, in which corresponding parts are indicated by like reference characters, 20 indicates two side sills of the supporting frame of the car, and 21 the end sills, such parts

being preferably formed of channel irons riveted together.

22 23 indicate four wide, heavy girders extending across between the side sills 20 to which they are suitably riveted, the upper edges of such girders being, as shown in Figs. 4, 5 and 6, flush with the upper edges of 60 the side sills. As shown in said Figs. 4, 5 and 6, these cross girders 22 and 23 extend a considerable distance below the sills of the car, and, at their ends, are inclined from the side sills inward. These girders are at opposite sides of discharge openings in the floor of the car, 65 through which openings the material in the car is discharged when the swinging doors, hereinafter more specifically referred to, are opened, and, when such doors are opened, said girders form effective guards for preventing the material that is being dumped from passing 70 off at the sides of the lowered doors, the doors and these girders forming, in effect, discharge chutes for the material, as will be well understood. The girders 23 are the inner ones or the ones nearest the center of the car, while the girders 22 are the ones nearest the ends of the 75 car. Each wide girder 22 23 is braced at each end by having riveted to it and to the under face of the adjacent side sill 20 a bracket 22^a and 23^a, respectively, as best shown in Figs. 1 and 3.

24 indicates the center sill of the car, the same being 80 made, in the form of construction shown, in two sections separated from each other, and the sill may, therefore, be properly termed an "interrupted" one. These sections extend outward from the girders 22. Each section is preferably composed of two parallel channel 85 irons, such channel irons being riveted to their respective girders 22. Each portion 24 of the central sill is left open at its outer end to receive suitable draft rigging. At their outer ends they are riveted, or otherwise attached, to the end sills 21, and are braced by intermediate cross sills or bars 25, the ends of which are suitably secured to the side sills and said central sills. 90

26 indicates the sides of the car, such sides being preferably formed of a number of plates of steel suitably riveted together and held considerably above and parallel with the side sills 20 by a series of steel bars 27 preferably formed of angle irons which are riveted to the outer face of the sills 20, as clearly shown in Fig. 1, and by a wider upright 27^a near each end, and a wider upright 27^b at the center, which wider uprights are preferably formed of channel irons. 95

28 indicates inclined braces riveted at their lower ends to the outer faces of the side sills and extending from the base of one upright piece to about the middle portion of the adjoining upright piece—the braces at 105 one side of the median line of the car extending toward one end of the car, while those on the other side of such line extend toward the opposite end of the car.

- 29 indicates the main floor of the car, which is preferably formed of plates of steel suitably united together. This floor section extends lengthwise of the car, its length being substantially equal to the distance between the side uprights 27^a. This floor has its sides parallel with and against the inside of the sides 26 of the car, as best shown in Fig. 4, the said floor being riveted to said car-sides, and, from about the lower edges of such sides 26, it is inclined rather sharply inward toward the longitudinal center of the car, and over the spaces between the two pairs of side cross girders 22 and 23, it is cut away, as clearly shown in Fig. 18, to form discharge openings which are normally covered by the swinging doors hereinafter described.
- 15 At each end of the car are located inclined floor-pieces 30, also formed of steel plates, such floor-pieces 30 each extending from near one end of the car to the opening in the main floor portion 29 so as to readily direct material in the car to such opening when the car is to be unloaded. As shown, the car is divided centrally into two separate portions or pockets by triangular shaped wings 31 (see Fig. 4) which are suitably riveted to the sides of the car-body. Leading from the lower edge of such wings 31 are short inclined floor pieces 32, that also act to direct material to the openings in the main floor sections. Both of the inclined portions of the main floor section 29 are braced from below by a flanged bar 33 extending lengthwise of the car at each side thereof, each of said bars being suitably riveted, or otherwise secured in place. Additional bracing to this main part of the floor is furnished at each side by two angle bars 34 spaced a distance apart. A set of these short angle bars is provided at each side over each of the wide beams 22 and 23, their lower ends resting upon a plate 35 58 that is riveted to the various sills and girders that constitute the supporting frame for the car-body.
- 35 indicates a small plate extending across the faces of each pair of short angle bars 34 to which it is riveted, such plate being also secured in any suitable manner—40 as, for example, by corner brackets, as in Fig. 13,—to the longitudinally extending brace bar 33.
- 55 indicates the plate hereinbefore mentioned. This plate, which in practice will be formed of a number of sheets riveted together, lies over and rests upon the supporting frame. It extends nearly the full length of the car, in the construction shown, it being riveted at its ends to the intermediate cross-sills or braces 25. This plate also extends from side to side of the supporting frame and is riveted along its side edges to the side sills 20. It is also riveted to the center sill 24 and to the tops of the heavy cross girders 22 and 23, thus effectually binding the various parts of the supporting frame together in such manner as to constitute it as a whole an extremely rigid structure, capable of resisting the great buffing and other strains that a car is constantly subjected to in use. In the central part of this plate 58 is formed an opening corresponding in size and shape to the opening in floor section 29.
- 60 Near each end of the car is provided a body bolster 35^a constructed in girder form as clearly shown in Fig. 7, each of said body bolsters resting on the plate 58 immediately over one of the cross-sills 25 so as to be firmly supported by such cross-sill. At its upper edge it is riveted to the inclined end floor section 30 and such floor sections are thereby suitably braced to withstand

any bending strains induced by the weight of the material placed in the car. The ends of this bolster are secured to the sides of the car-body as shown, and thus the stresses or strains are so transmitted as to be equally distributed through these girder-like sides.

70 35^b indicates a block formed of angle irons riveted together, or formed in any other desired manner, such block being secured between the two parallel members of the central sill 24—a block 35^b being provided at each end of the car. These blocks are adapted to rest upon a truck-bolster (not shown) and connected therewith by a pin as usual.

36 indicates the swinging doors, a pair of such doors being adapted, when drawn up, to completely close the opening in the car floor between one of the pairs of heavy girders 22 23. Each pair of doors is attached by a pivot 37 passing through its side bar and through the adjacent cross-girder 22 or 23. The plate forming the wearing surface of one of each pair of these swinging doors is turned to extend over the line of the pivots 37, 80 as clearly shown in Figs. 4, 5 and 6, so as to effectually prevent any of the material carried by the car from getting onto the pivots. From the different positions of the doors shown in Figs. 4, 5 and 6, it will be seen that, no matter what position the doors may be moved to with 85 relation to each other, the pivots are at all times effectually guarded. When the doors are both in their raised position, as in Fig. 5, it will be seen that their upper surfaces are in direct line with the sharply inclined floor section 29, and, when one only of such 90 doors is lowered, as in Fig. 4, the lower door will be in a direct line with the closed door, and hence a sharp incline will be furnished for discharging the entire contents of the car at that side of the central division wings 31, so that all of the material in that compartment or 95 pocket of the car must be quickly discharged at one side of the car. When both doors are down, as in Fig. 6, the contents of that compartment or pocket of the car will be discharged evenly at opposite sides of the track. These various doors are operated through the medium 100 of chains—which, together with the devices for exerting a pull upon the chains, will be hereinafter specifically referred to—and it is well known that where chains are employed in such work it is not uncommon for them to stretch and lengthen on account of the heavy strains 105 to which they are subjected. This lengthening of the chains is often sufficient to cause the doors to stand open a number of inches, and so render the car unfit for the transportation of dirt, gravel, coal, and various other kinds of material, owing to the danger of losing such material through the crack or opening left by the partially-closed door. By my construction, the chains may lengthen several inches and the free edges of the doors sag or drop correspondingly without leaving a crack or opening sufficiently large to permit of the escape of material such as mentioned, and this is due to the fact that the longitudinally-extending flanged bars 33 are so located and inclined that the edges of the doors are close to them during the first part of the downward swing of such doors, and as such bars 33 are quite wide 115 it will be seen that the chains will have to stretch or lengthen very considerably before the doors can swing below these bars, and until the doors have swung below them there will be but very little opening through which material can escape.

The means for operating the doors on one side of the car are the same as those on the other side, and hence a description of the mechanism for operating the doors on one side will be sufficient. Referring to such operating means, 38 indicates chains, one attached at each lower corner of each door 36, the attachment to the doors being, in the construction shown, through the medium of a lug 39. Each of these chains passes over a pulley 40 that projects through a slot in one of the supporting angle bars 33, such pulley being journaled in the plate 35 and one of the corner brackets before mentioned which connects such plate with the longitudinally extending angle bar 33 (see Figs. 9 and 13). Each of these chains, after passing over its pulley 40, passes around another pulley that is located a little nearer to the side of the car than the first pulley, such second pulley being indicated by 41 and having its axle journaled between flanges 42 formed on one of the plates 35. The axles of the pulleys 41 are at right angles to the axles of the pulleys 40 in order that the chains may be pulled longitudinally of the car by the devices about to be described. The end of each one of these lifting chains 38 has connected to it a short screw-threaded stem 43 which (with the exception of that one of the four chains 25 on each side that is nearest to the hand-wheel herein-after described) passes through a yoke 44 that is secured by a pin 45 to a pair of parallel sliding bars 46, the stem 43, as shown (see Fig. 13) having a nut or nuts on its screw-threaded portion so as to properly adjust the 30 chain connected therewith as required. There are two swinging doors on each side of the car, as stated, and there are four separate chains, two for each door, and each of them is connected with the pair of parallel sliding bars through a separate yoke 44, except that one 35 nearest to the operating wheel. That last-mentioned chain, after passing around its two pulleys 40 and 41, in the manner stated, has its connecting stem 43 passed through an ear 47 that is made fast to or formed with another and longer yoke 48 that embraces and has secured 40 to it an elongated nut 49 through which passes a long screw-threaded rod 50, the screw-threads of which are, as best shown in Fig. 13, quite sharply inclined. The yoke 48 and nut 49 are incased in a long box 51 open at its inner end to receive the ends of the parallel operating rods 46 and the forward one of the chains 38. This 45 box is secured to the under face of one of the sloping sides of the main floor section 29, by rivets, bolts, or otherwise. I have shown and described the doors as provided with chains by which they may be lifted, but cables of course might be employed in place of chains. 50

52 indicates a fixed bearing carried at the inner end of the box 51, in which the smooth unthreaded portion of the rod 50 rests, the rod being held against longitudinal movement by a key 53 passing through the rod. 55 indicates a nut screw-threaded onto the outer end of the rod 50 and secured thereto by a key, as shown, or otherwise. 55 indicates a hand-wheel on the end of the rod. 56 indicates small angle irons so placed in the box 51 as to prevent sidewise movement of the pair of parallel bars 46 and their attached yoke 44, and at the same time forming a slot between them to allow of the lateral projection of the ear 47 (see Fig. 10). Each of the pulleys 41, except the forward one, is so located with reference to the sliding parallel bars 46 as

to bring the link 43 carried by each chain between the said parallel bars, but the forward one of these four pulleys is located (see Fig. 13) so that the chain passing around it passes at one side of the parallel bars in order that its link may be brought into position to properly 70 pass through and exert a straight pull upon the ear 47 that projects out, as stated, from the long yoke 48. It is necessary to do this in the construction shown in order to avoid contact of the forward link 43 with the screw-threaded rod 50. The pulling effect, however, of this 75 forward chain on the parallel bars is substantially the same as the pull of the other chains on such bars. These parallel sliding bars extend, as stated, longitudinally of the car, and for the greater portion of the length of the car. They are guided and held in place by passing 80 through suitable shaped openings in the several plates 35 and by passing between the short flanged brace bars 34 which are spaced apart sufficiently to permit the said sliding bars to move freely. The flanges on these short brace bars aid in acting as guides for the sliding 85 bars, as best shown in Figs. 9 and 13.

57 indicates a pivoted latch carried on the supporting frame work of the car and adapted to be thrown between the spokes of the operating wheel 55 so as to lock such wheel and the shaft keyed thereto from rotation. Any 90 other suitable device for effecting the locking of these parts may be employed.

When it is desired to discharge the material from the car, that one of the hand-wheels 55 at the side where the material is to be dumped is to be released from engagement with its latch 57; and, inasmuch as the pitch of the screw on the shaft 50 is a sharp one, the pressure of the load on the doors at that side of the car will, through the pulling strain exerted through the chains 38 and the pair of sliding bars 46 to which they are attached, pull the nut 49 carried by the yoke 48 backward on the screw shaft 50 sufficiently to cause such shaft to rapidly revolve—such turning of the shaft, of course, carrying the nut towards the inner end of said shaft. The inward movement of this nut in this manner, of course, allows the pivoted doors to swing on their pivots, and, by the time that the nut has reached the inner end of its screw-threaded shaft 50, the doors will have reached their lowermost position, as, for example, in Fig. 4, and when in that position will be brought 100 to rest against suitable stops 58a preferably formed of pieces of angle iron riveted to the inner faces of the heavy cross-girders 22 and 23. It is to be understood that if the dumping of the material is to be at one side only, but one of the wheels 55 is to be unlatched, but 110 if the dumping is to be at both sides, both wheels will be released at the same time. After the load has been discharged, the doors are to be raised into their closed position, as in Fig. 5, by an attendant turning the hand-wheel 55. The result of such turning is, of course, to 120 cause the nut 49 to be moved in the box 50 towards the outer end of such box, and as the sliding bars 44 are bolted to the yoke 48 that carries such nut such sliding bars will be correspondingly moved and also exert the required pull on the several chains 38 that 125 are connected with such sliding bars.

The sides 26 of the car, owing to their method of construction, form, in effect, girders, and, by bracing them in the manner described and connecting them with the supporting frame work formed by the sills, an ex- 13

ceedingly strong construction is insured, enabling the car to withstand heavy shocks incident to the character of the work in which it is engaged.

From the drawings and the specific description of the several parts hereinbefore given, it will be seen that at each side of the car there is formed a column-like construction disposed horizontally and in length equaling the distance between the two body bolsters 35"—such column-like structure being of irregular shape and having its sides formed of the channel iron 35, the inclined floor section 29, the plate 58 and the braces 27, 28, 27^a and 27^b, in which column-like structure are housed the mechanism for operating the pivoted doors, access to which mechanism is readily obtained at any time between the braces specified. In addition to this construction affording a housing for the parts, it so stiffens the car as a whole as to render it capable of resisting the great compressive and other strains to which such a car is constantly subjected in use. Furthermore, in addition to what has been stated, it will be understood that by reason of the plate 58 being riveted to the various sills of the supporting frame and the inclined floor section 29 resting upon the said plate and secured in place by rivets to the said plate and the cross-girders and intermediate sills, the supporting frame as a whole and the car-body as a whole are so rigidly connected together that all stresses and strains are perfectly distributed through the entire car structure.

30 What I claim as my invention and desire to secure by Letters Patent is:—

35 1. In a side-dump car, the combination with a floor section inclined from each side of the car downward toward the longitudinal center of the car and provided with a discharge opening in each inclined portion, of two doors pivoted at substantially the longitudinal center of the car, cross-girders at each side of each door to direct all of the material discharged from the car and over the doors to the side of the car-track, lifting chains for the doors, devices 40 movable longitudinally of the car to which said chains are connected, and means for moving said longitudinally movable devices to operate the doors, substantially as described.

45 2. In a side-dump car, the combination with a suitable supporting frame comprising side and end sills, of a car-body comprising sides, ends and a floor, said sides being held above and away from the said side sills, and said floor being inclined from the said sides toward the longitudinal center of the car and provided with a discharge 50 opening in each inclined portion, two doors pivoted at substantially the longitudinal center of the car, lifting chains for the doors, devices located in the spaces between the inclined floor and the supporting frame, to which devices said chains are connected, and means for moving said devices longitudinally of the car to operate the doors, substantially as described.

55 3. In a side-dump car, the combination with a suitable supporting frame comprising side and end sills, of a car-body comprising sides, ends and a floor, said sides being held above and away from the said side sills, and said floor being inclined from the said sides toward the longitudinal center of the car and provided with a discharge opening in each inclined portion, two doors pivoted at substantially the longitudinal center of the car, lifting 60 chains for the doors, longitudinally-movable bars beneath the inclined portions of the floor to which bars the said chains are attached, guides in which said bars are supported, and means for moving said bars, substantially as described.

65 4. In a dump-car, the combination with a suitable supporting frame comprising side and end sills, of a car-body comprising sides, ends and a floor, said sides being held above and away from the said side sills, and said floor

being inclined downward from the sides towards the center and having discharge openings therein, swinging doors 75 for said openings, lifting chains for the doors, and means located in the spaces between the inclined floor and the said supporting frame for operating the doors by pulling on the chains, substantially as described.

5. In a dump-car, the combination with a suitable supporting frame comprising side and end sills, of a car-body 80 comprising sides, ends and a floor, said sides being held above and away from the said side sills, and said floor being inclined downward from the sides towards the center and having a discharge opening therein, cross-girders 85 at opposite sides of said opening, said girders being connected at their ends to the said side sills and extending below the same, doors pivoted between said cross-girders, lifting chains connected to said doors, and means located in the spaces between the inclined floor and the said supporting frame for raising the doors by exerting a pull on said chains, substantially as described.

6. In a side-dump car, the combination with an inclined floor section having an opening therein, of a pivoted door 95 for closing such opening, lifting chains for the door, a longitudinally movable member located beneath the inclined floor and to which said chains are connected, of a screw-threaded rod located at one end of the car and extending longitudinally thereof, a nut on said rod, means for holding said nut against rotation, means for connecting said longitudinally movable member with the nut, and a hand-operated device for turning the screw-threaded rod, substantially as described.

7. In a side-dump car, the combination with an inclined floor section having a discharge opening therein, of a pivoted door for closing such opening, a rotatable screw-threaded rod extending longitudinally of the car and supported in bearings at one end of the car, a nut on said screw-threaded rod, means for holding said nut against rotation, and means connected with said nut and door for 100 causing the moving of the door when said nut is moved on said rod, substantially as described.

8. In a side-dump car, the combination with an inclined floor section having a discharge opening therein, of a pivoted door for closing such opening, a box or casing 115 secured to the under face of said inclined floor and extending longitudinally of the car, a rotatable screw-threaded rod journaled in said box or casing, a nut on said screw-threaded rod, means for holding said nut against rotation, and means connected with said nut and door for causing the moving of the door when said nut is moved on said rod, substantially as described.

9. In a side-dump car, the combination with an inclined floor section having a discharge opening therein, of a pivoted door for closing such opening, a box or casing 125 suitably supported at one end of the car and located beneath the inclined floor and extending longitudinally of the car, a rotatable screw-threaded rod journaled in said box or casing, a nut on said screw-threaded rod, means for holding the nut against rotation, a rod connected at one of its ends with said nut and extending longitudinally of the car, chains connecting said rod and door, and pulleys over which said chains pass, substantially as described.

10. In a side-dump car, the combination with an inclined floor section having a discharge opening therein, of a pivoted door for closing such opening, a box or casing 135 suitably supported at one end of the car and located beneath the inclined floor and extending longitudinally of the car, a rotatable screw-threaded rod journaled in said box or casing, a nut on said screw-threaded rod, a yoke embracing said nut, a rod connected at one of its ends to said yoke and extending longitudinally of the car, chains connecting said rod and door, and pulleys over which said chains pass, substantially as described.

11. In a side-dump car, the combination with an inclined floor section having a discharge opening therein, of a pivoted door for closing such opening, a box or casing 145 suitably supported at one end of the car and located beneath the inclined floor and extending longitudinally of the car, a rotatable screw-threaded rod journaled in said box or casing, a nut on said screw-threaded rod, a yoke embracing said nut, and having a laterally-projecting lug, a rod connected at one of its ends to said yoke and ex-

- tending longitudinally of the car, a lifting chain connected at each side of the door, one of said chains being connected to the rod and the other chain to said lug, and pulleys over which said chains pass, substantially as 5 described.
12. In a side-dump car, the combination with an inclined floor section having a discharge opening therein, of a pivoted door for closing such opening, a box or casing suitably supported at one end of the car and located 10 beneath the inclined floor and extending longitudinally of the car, a rotatable screw-threaded rod journaled in said box or casing, a nut on said screw-threaded rod, a yoke embracing said nut, and having a laterally projecting lug, two parallel bars secured to opposite sides of 15 said yoke and extending longitudinally of the car, a lifting chain connected at each side of the door, one of said chains being attached to said lateral lug, a second yoke secured between the pair of parallel bars to which last named yoke the other chain is connected, and pulleys over 20 which said chains pass, substantially as described.
13. In a side dump car, the combination with an inclined floor section having an opening therein, of a pivoted door for closing such opening, lifting chains for the door, a longitudinally-movable bar located beneath the inclined 25 floor, guiding pulleys over which the chains pass, a connection for each chain with the bar, guides for supporting the bar, and means for moving the bar to operate the doors, substantially as described.
14. In a side-dump car, the combination with an inclined floor section having an opening therein, of a pivoted 30 door for closing such opening, lifting chains for the door, a pair of parallel longitudinally-movable bars located beneath the inclined floor, guiding pulleys over which the chains pass, a connection for attaching one of the chains 35 between the bars, another connection for connecting another of the chains with the bars at one side of said bars, and means for moving the bars to operate the doors, substantially as described.
15. In a side dump car, the combination with an inclined floor section having an opening therein, of a pivoted 40 door for closing such opening, and a fixed member adjacent to such floor-opening adapted to aid in checking the escape of material from the car until the door has swung past such member, substantially as described.
16. In a side dump car, the combination with an inclined floor section having an opening therein, of a pivoted 45 door for closing such opening, and a fixed inclined member adjacent to such floor-opening adapted to aid in checking the escape of material from the car until the door has 50 swung past such member, substantially as described.
17. In a side dump car, the combination with a supporting frame comprising side and end sills, of a car-body comprising sides and ends and an inclined floor, said floor having a discharge opening through it, a pivoted 55 door for closing such opening, lifting chains for said door, a fixed bar extending longitudinally of the car and connected with both the said supporting frame and inclined floor and located at one side of said floor-opening,
- said bar being provided with openings through which said chains may pass, pulleys for guiding said chains, and means for exerting a pull on said chains in the direction of the length of the car, substantially as described. 60
18. In a side-dump car, the combination with a suitable supporting frame comprising side and end sills, of a car-body comprising sides, ends and a floor, said sides being held above and away from the said side sills, and said floor being inclined from the said sides towards the longitudinal center of the car and provided with a discharge opening in the inclined portions, braces between the said supporting frame and the under side of the inclined portions of 70 the floor, doors for closing the opening in the floor, lifting chains attached to the doors, a longitudinally-movable rod located at each side of the longitudinal center of the car and guided by the said braces, means for attaching the said chains to said rods, and means for moving the rods to operate the said doors, substantially as described. 75
19. In a side dump car, the combination with a supporting frame comprising suitable sills, a plate affixed to the upper faces of said sills and provided with a discharge opening therethrough, of a car-body comprising sides, 80 ends and a floor, said sides being held above and away from the said side sills and said floor being inclined from the said sides towards the longitudinal center of the car and provided with a discharge opening over the opening in the said plate, braces between the said supporting 85 frame and the under side of the inclined portions of the floor, doors for closing said openings, lifting chains attached to the doors, a longitudinally-movable device located at each side of the longitudinal center of the car and guided by the said braces, means for attaching the 90 said chains to said longitudinally-movable devices, and means for moving said last-named devices to operate the said doors, substantially as described.
20. In a side dump car, the combination with a supporting frame comprising suitable sills, a plate affixed to the upper faces of said sills and provided with a discharge opening therethrough, of a car-body comprising sides, ends and a floor, said sides being held above and away from the said side sills and said floor being inclined from the said sides towards the longitudinal center of the car and provided with a discharge opening over the opening in the said plate, a beam at each side of the car extending longitudinally thereof and serving as a brace between the said supporting frame and the inclined floor, braces connected to the side sills and the sides of the car-body, 95 whereby a horizontal hollow column is formed at each side of the car consisting of said plate, beam, inclined floor and braces, a longitudinally-movable device located within each of said hollow columns, doors for closing the said discharge openings, and chains connected to said 100 doors and to said longitudinally-movable devices, substantially as described. 105
